DENTAL MATRIX APPARATUS

Donald R. Christie and Merton M. Bottemiller,
Wadena, Minn.

Application June 17, 1950, Serial No. 168,702

3 Claims. (Cl. 32—63)

1

The present invention is particularly concerned with dental matrix apparatus of the type designed for use in the filling of cavities in anterior teeth. It is common practice to fill cavities in the anterior teeth with either a "porcelain" or plastic material which resembles the tooth in appearance and hence is not as conspicuous as would be fillings of other types. In order to properly shape such a filling, it has been customary to manually hold in place closely adjacent to the filling a tape of thin material such as cellophane or regenerated cellulose. This has required the continued effort of the dentist until the filling has become set. If the dentist's hand became tired to the point where it permitted the tape to move a bit, then the filling tended to be unsatisfactory. With the newer plastic filling materials, the setting time is sufficiently long that the time required for the tape to be held in place becomes a substantial portion of the total time required for filling the tooth.

An object of the present invention is to provide a matrix band and clamp which may be used with fillings in anterior teeth and will remain in place without continued manual assistance.

A further object of the present invention is to provide such a matrix band and clamp in which the band is adhesively maintained in place while the clamp is being applied.

A still further object of the invention is to provide such a matrix band apparatus in which the clamp is so formed as to be readily placeable in clamping position.

These and the other objects of our invention, which will be apparent from the following description, are accomplished by providing a tape which has adhesive on the end portions thereof and an intermediate portion free of adhesive which is placed against the filling, with the adhesive ends of the tape doubled over and pressed into adhesive engagement with the tooth being filled and with one or more adjacent teeth. The clamp is so formed as to be placed into engagement with the tape closely adjacent the filling, but overlying the adhesive portion of the tape so as to cause the tape to adhere even more firmly to the tooth being filled. Further details of the invention will be described in connection with the accompanying drawing of which.

Figure 1 is an isometric view of our improved matrix tape or band;

Figure 2 is a vertical sectional view of the clamp forming part of our matrix band apparatus;

2

Figure 3 is a transverse sectional view of the clamp, the section being taken along the line 3—3 of Figure 2;

Figure 4 is a view showing a number of anterior teeth including one of which has been drilled for a filling, and with our improved matrix band in position for the insertion of the filling material, the view being taken from the rear side of the teeth;

Figure 5 is a front view of the same teeth as shown in Figure 4, showing a filling material in position in the cavity;

Figure 6 is a front view of the same teeth with the free end of the band looped over the cavity and pressed into engaging relation with the teeth;

Figure 7 is a view showing the clamp in position, and

Figure 8 is a sectional view of the clamping faces of the clamp, the tape, and the teeth.

Referring to the drawing, the matrix band of our invention is designated by the reference numeral 10, and is best shown in Figure 1. The band 10 consists of a tape 11 having the end portions thereof covered with adhesive layers 12 and 13. The tape 11 is preferably formed of some transparent plastic material such as cellophane. The adhesive layer 12 is covered with a protective tape 14, and layer 13 with a similar protective tape 15. The adhesive layers 12 and 13 may take any suitable form. For example, they may be in the form of a double coated tape, one surface of which is pressed into engagement with the tape 11. Or, the adhesive layer may take the form of a simple layer applied directly to the tape 11. It is to be noted that the adhesive portions 12 and 13 terminate adjacent the central portion 16 of the tape. It is this adhesive-free, central portion which is designed to be placed adjacent the filling. Since it is not desired that the tape adhere to the filling proper, this portion is not adhesive. It is to be understood, of course, that the thickness of the layers is exaggerated in the drawing and that in actual practice, there is no substantial difference in thickness between the adhesive coated portions and the central portion 16.

Referring now to the clamp, this is best shown in Figures 2, 3, and 7. The clamp, which is designated in its entirety by the reference numeral 20, is formed of a strip 21 of resilient metal having a U-shaped body portion 22 and two end clamping portions 23 and 24. Rigidly secured to one leg of the U-shaped body portion 22, is a rod 27 terminating in a finger piece 28. Secured to the other leg of the body portion 22 of strip 21,

is another rod 30, terminating in a finger piece 29. Rod 30 extends through an elongated slot 32 in the leg to which rod 27 is fastened, so that finger pieces 28 and 29 are opposite to each other and may be conveniently engaged by thumb and forefinger.

Secured to the adjacent faces of clamping portions 23 and 24 are a pair of rubber clamping members 34 and 35, respectively. These clamping members have opposed spherically curved faces and are formed of yieldable material having an abrasive therein. The purpose of the abrasive is to cause the clamping members to remain in position on the plastic tape 11 and not to slide with respect thereto.

It will be readily apparent from the dotted line position of a portion of the clamping member, as shown in Figure 2, that by grasping the fingerpieces 28 and 29 between the thumb and forefinger and squeezing them together, the upper leg of the strip 21 is flexed upwardly to cause separation of the clamping members 34 and 35. This permits the clamp to be placed in position. Upon release of the fingerpieces 28 and 29, the clamping members 34 and 35 are moved together into clamping relation by reason of the resilience of the strip 21. Since the clamp may be manipulated by the fingers of one hand, the other hand is entirely free to hold the band 10 in position while the clamp is being applied.

Referring now to Figure 4, the band 10 is shown partially applied in connection with a filling in one of the upper anterior teeth. The view is taken as though the upper jaw were swung back through an angle of about 135° for convenience in viewing the cavity. The tooth being filled is designated by the numeral 40. The teeth on the left side (opposite the cavity) are designated by numerals 41, 42, and 43 while that on the right side of the tooth is indicated by numeral 44. The cavity is indicated by numeral 48 and it will be assumed that the cavity of Figure 4 has been drilled and properly treated for receiving the filling. As shown in Figure 4, the tape 10 has had the covering strip 14 removed so as to expose the adhesive layer 12. The strip has been placed in position with the intermediate portion 16 adjacent to the filling 48 and with adhesive layer 12 firmly pressed against the rear surfaces of teeth 40, 41, and 42.

Referring now to Figure 5, the same upper anterior teeth are shown from the front with the filling material 49 in position in the cavity. This filling material may be of the so-called "porcelain" type or the newer plastic type. As indicated by the drawing, the filling material has been applied with the righthand portion of the band 10 moved back out of the way of the cavity. As also indicated in the drawing, the filling material 49 is applied to the cavity in a quantity such as to project slightly beyond the normal contour of the cavity preparation.

The protective strip 15 is now removed, exposing the adhesive layer 13. At the same time the righthand end of the strip is drawn around the tooth 40, spreading out the filling material 49, as shown in Figure 6. The adhesive layer 13 of the band is then pressed into engagement with the forward surface of the teeth. The band is now in the position shown in Figure 6. Due to the absence of any adhesive or other covering material on the intermediate portion 16, this portion is transparent. Hence, a good view is obtained through this portion of the filling 49 as the band 10 is pulled into position.

While the band tends to remain in the position shown in Figure 6 due to the adhesive layers 12 and 13, it is desirable to clamp the band in position. The fingerpieces 28 and 29 are squeezed together to separate the clamping jaws 34 and 35, as best shown in dotted lines in Figure 2. The clamp can then be placed in position adjacent the cavity. Upon the fingerpieces 28 and 29 being released, the clamping faces 34 and 35 are pressed firmly into engagement with the band 10 to hold the band in engagement with the tooth. A portion of the clamping faces 34 and 35 will overlie the adhesively coated portions of band 10 to maintain the transparent portion of the band in close adherence to the tooth 40. The relation of the clamping jaw surfaces 34 and 35 to the band 10 and the teeth is best indicated in the sectional view of Figure 8. It will be seen from this view that the band 10 is held in close engagement with the tooth so that the filling is molded so as to conform with the contour of the tooth. Since the clamp is mechanical, the pressure maintained on band 10 will be constant throughout, and there is no tendency for the band to shift as occasionally happens when the band is manually held. The abrasive in the clamping members 34 and 35, furthermore, prevents any shifting of the clamp on the band.

Due to the angle at which the clamping portion 24 extends with respect to the body portion 22, the latter tends to project forwardly in the mouth and hence clears the opposing jaw. This is desirable in that it aids in placing the clamp in position. The spherically curved surfaces of clamping members 34 and 35 also increase the flexibility in the positioning of the clamp in the mouth. Because of the curvature of the clamping members, the clamping device can be tilted without impairing the clamping action.

It will be seen that we have provided a matrix band and clamp for use with anterior teeth in which it is possible to maintain the band in position without continued manual effort. It will furthermore be seen that this is accomplished by the use of a relatively simple type of band and a clamp of simple construction which is readily manipulatable with only one hand.

While we have shown a specific form of our invention for purposes of illustration, it is to be understood that the invention is limited only by the scope of the appended claims.

We claim as our invention:

1. A dental matrix comprising a long band of relatively uniform width and formed of thin flexible material having adhesive material on the end portions thereof and having an intermediate portion free of adhesive for the full width of the band and adapted to engage a filling, said band being adapted to be looped around a tooth with the intermediate non-adhesive portion engaging a filling and with the adhesive portions adhering to the tooth.

2. A dental matrix band of thin flexible material of a length at least three times the width of a normal anterior tooth and of relatively uniform width, said band having adhesive material on the end portions thereof and having an intermediate portion free of adhesive for the full width of the band and adapted to engage a filling, said band being adapted to be looped around a tooth with the intermediate non-adhesive portion engaging a filling and with the adhesive portions adhering to the tooth being filled and at least one tooth adjacent thereto.

3. A dental matrix comprising a long band of

relatively uniform width and formed of thin flexible transparent material having adhesive material on the end portions thereof and having an intermediate portion free of adhesive for the full width of the band, said band being adapted to be looped around a tooth with the intermediate non-adhesive portion engaging a filling and with the adhesive portions adhering to the tooth, the filling being visible through the intermediate non-adhesive transparent portion.

10
